UNITED STATES PATENT OFFICE.

SIGWARD SIMONSON, OF BUTLER, PENNSYLVANIA, ASSIGNOR TO HARRY VISSERING & COMPANY, OF CHICAGO, ILLINOIS, A CORPORATION OF ILLINOIS.

MANUFACTURE OF RAILWAY DRAFT-GEAR.

1,352,152.

Specification of Letters Patent. Patented Sept. 7, 1920.

Application filed May 7, 1918. Serial No. 233,022.

To all whom it may concern:

Be it known that I, SIGWARD SIMONSON, a citizen of the United States, and a resident of Butler, in the county of Butler and 5 State of Pennsylvania, have invented certain new and useful Improvements in the Manufacture of Railway Draft-Gears, of which the following is a full, clear, and exact description.

10 The invention relates to the manufacture of yokes and keys for railway draft-gears.

One object of the invention is to provide a method of making forged one-piece draw-bar yokes comprising integral sides having 15 openings therein to receive the draft-gear.

Another object of the invention is to provide an improved method of economically forming a one-piece forged yoke which is complete in itself and is formed so that 20 separate transverse connections, such as are necessary in a sectionally formed yoke, will not be required.

A further object of the invention is to provide an improved method of making 25 forged draw-bar yokes in which key-pins for securing the yokes to coacting elements are formed of cut-outs from the blank for the yoke, thus reducing the cost of production and effecting a saving of metal.

30 Other objects of the invention will appear from the practice hereinafter set forth.

The invention consists in the several novel features hereinafter set forth and more particularly defined by claims at the conclusion hereof.

In the drawings: Figure 1 is a perspective view of a bar of metal or stock which forms a blank for the yoke and keys. Fig. 1^a is a cross-section of the blank. Fig. 2 is 40 a perspective view showing the yoke-blank after the key-blanks have been cut therefrom and the ends have been slotted and shaped. Fig. 3 is a perspective view of one of the cut-out sections which forms a key-blank. Fig. 4 is a perspective view of the 45 key cut and shaped from the blank shown in Fig. 3. Fig. 5 is a perspective view of the finished yoke and after the blank has been doubled or bent medially to form the integral sides, each side having an opening 50 therein for the follower plates for the draft-gear and for the coupler-shank key. Fig. 6 is a plan, parts being shown in section, of a draft-gear embodying the yoke and key 55 made in accordance with the improved

method. Fig. 7 shows a blank for a modified form of yoke.

The improved method consists in forming the yoke of a bar 10 preferably of rolled steel or wrought iron. Said bar has top and 60 bottom flanges 11 and 12, and a web 13 with a thickened zone or longitudinal rib 14, the flanges and web being integral. The web portions 13^a extend diagonally from the outer face of the flanges to the inner edges 65 of the rib 14. The bar is in substance, a channel-bar with a thickened central rib 14 and is formed by a suitable rolling process. These bars are of sufficient length to form the back and both sides of a draw-bar yoke 70 and may, if desired, be cut from long lengths of stock.

Two sections 15 are cut or punched out of the ribbed web 13, leaving openings 16 in the yoke blank, as shown in Fig. 2. These 75 openings are spaced apart to leave a vertical connecting or columnar portion 17 between the top and bottom flanges, medially of the blank. This portion 17 is adapted to be formed into the back or connecting-portion 80 between the yoke-sides with a columnar portion between the top and bottom flanges.

The front ends of the blank 10 are cut off, as at 18, on convergent lines to form narrowed ends at the sides of the coupler-shank 85 respectively. A longitudinal key-slot 19 is punched or formed adjacent each end of the blank 10 for the key which connects the coupler-shank and yoke. The metal adjacent the outer end of each key-opening is swaged 90 or upset, as shown at 20, to provide an enlarged or reinforced bearing projecting from the outer face of the blank for the front of the key. In forging the end portions of the blank, the rib portions 14 between the outer ends of the openings 16 and the ends of the blanks, are forced outwardly 95 so that the inner face of the web of the blank will be substantially flat, and the metal then projecting from the outer face of 100 the blank is cut away or utilized in the reinforcement 20. This shaping is effected to avoid excessive thickness in the yoke at the sides of the coupler-shank, and to leave sufficient clearance between them and the usual 105 front-stops for the front follower-plate.

When these cutting and shaping steps have been performed, the blank will be of the form shown in Fig. 2 of the drawing.

Next, the blank will be bent or doubled 110

- transversely on a medial line to form sides in juxtaposition, as shown in Fig. 5. In this operation, the openings 16 are brought into transverse alinement with each other and the 5 key-slots 19 are also brought into transverse alinement. This bending operation forms the blank into a yoke with two sides which are integral and which has continuously extending flanges 11 and 12 and an integral 10 connecting or columnar portion 17 between the flanges. The back of the yoke is preferably semi-circular in form and the sides are flared from the rear toward the front. The back edges of the openings 16 in the connecting web portion of the yoke will be properly disposed to hold the rear buffer or follower plate 28 and the front edges of said openings will be disposed to engage the front follower plate 27, the openings 13, extending substantially between the flanges, 15 will be of sufficient height so that the draft-gear can be inserted laterally into the yoke and to space the yoke-sides apart transversely to receive and retain the draft-gear. 20 The yoke-sides extend directly and angularly from the back of the yoke to the sides of the coupler-shank. With this formation, the stresses between the back and the front of a one-piece yoke are directly applied. 25 This method thus exemplifies one for producing a forged one-piece yoke in which the sides are formed with openings for the buffer mechanism and with key-slots. 30 The thin portions of the cut-out sections 35 15 disposed above and below the thick portion 14 are sheared off and the cross-sectional area of this thick portion is substantially of the correct dimensions to form a key 22 which is adapted to connect the yoke and 40 the coupler-shank. After the thin marginal portions of the blank 15 have been cut away, the edges of the remaining portion will be suitably shaped or cut and one end may be bent, as at 22^a to form a head thereon to 45 form a complete key.
- A characteristic of forming the rib 14 on the yoke blank is that while the portions thereof remaining in the yoke are utilized in reinforcing the back of the yoke, the 50 cut-outs are used to form keys. By using a blank which is formed so that the cut-out portions may be utilized as keys, the wastage in a forged yoke is greatly lessened and the cost of production is substantially reduced. 55 This method provides for the production of two key blanks for each yoke, and if but one is utilized in the make-up of the draft-gear, the other may be kept in reserve for replacement of a broken one.
- 60 In Fig. 6, the product of the invention is shown as applied to a draft gear comprising a coupler having a shank 24 secured to the yoke by key 22. The latter, as well understood in the art, extends also through the 65 draft-beams 25. Front stops 26 are engaged

by the front follower-plate 27, and the rear follower-plate 28 engages rear-stops 30 on the draft-beams. A suitable draft-gear 29 of any suitable type, such as a friction or spring gear, is interposed between the follower plates, as well understood in the art. The follower plates and draft-gear 29 are all insertible laterally into the yoke through openings.

Fig. 7 shows the shape given to the blank 75 when the yoke is to be used for tandem buffer-mechanism. Four openings 16^a are cut into the web of the blank. This blank, after its ends have been shaped and the key slots have been cut therein in the same 80 manner as hereinbefore described, is bent around a median transverse line to bring the key-slots and openings 16^a into transverse alinement. Each alined pair of openings is adapted to receive and retain one 85 element of a tandem draft-gear of any suitable construction.

The invention exemplifies an improved method for the manufacture of forged draft-gear yokes in which the two sides, each having one or more openings therein for the follower plates and draft-gear are integrally formed out of a blank of wrought metal. Also a method by which a flanged bar is doubled or bent transversely, with its flange 95 inside, to form a one-piece forged yoke. Also a method in which cut-outs from the yoke-blank are forged into keys.

The invention is not to be understood as restricted to the details set forth, since these 100 may be modified within the scope of the appended claims, without departing from the spirit and scope of the invention.

Having thus described the invention, what I claim as new and desire to secure by Letters Patent, is:

1. That improvement in making railway draft-gear yokes which consists in forming a blank of metal of sufficient length to form the sides and back of a yoke, shaping and forming reinforcements on the end portions of the blank for attachment to a coupler-shank, cutting draft-gear openings in the blank, and bending and doubling the blank about its medial portion to form a one-piece 110 yoke and to bring the openings into juxtaposition to form a draft-gear pocket in the yoke.

2. That improvement in making railway draft-gear yokes which consists in forming a blank of metal of sufficient length to form the sides and back of a yoke with marginal flanges at the top and bottom thereof, shaping and forming reinforcements on the end portions of the blank for attachment to a 120 coupler-shank, cutting draft-gear openings in the web of the blank, and bending and doubling the blank about its medial portion to form a one-piece yoke with the flanges forming the top and bottom thereof and so 130

as to bring the openings into juxtaposition and form a draft-gear pocket in the yoke.

3. That improvement in making railway draft-gear yokes which consists in forming a blank of metal of sufficient length to form the sides and back of a yoke with marginal flanges at the top and bottom thereof and a connecting web having a thickened central zone, shaping and forming reinforcements on the end portions of the blank for attachment to a coupler-shank, cutting draft-gear openings in the web of the blank, and bending and doubling the blank about its medial portion to form a one-piece yoke with the thickened zone forming a portion of the back and the flanges forming the top and bottom thereof and to bring the openings into juxtaposition to form a draft-gear pocket in the yoke.
- 20 4. That improvement in making railway draft-gear yokes which consists in forming a blank of metal of sufficient length to form the sides and back of a yoke with marginal flanges at the top and bottom thereof, shaping and forming reinforcements on the end portions of the blank for attachment to a coupler-shank, cutting draft-gear openings in the web of the blank and bending and doubling the blank about its medial portion to form a one-piece yoke with flanges inwardly of the web and to bring the openings into juxtaposition to form a draft-gear pocket in the yoke.

5. That improvement in the manufacture 35 of making railway draft-gear which consists in punching a section out of a yoke-blank to form a draft-gear opening in the

blank, shaping the blank for keying to a coupler-blank, and shaping the punching into a key for attaching the yoke to the shank.

6. That improvement in the manufacture of draft-gear which consists in punching out of the web of a marginally flanged yoke-blank to form a draft-gear opening in the blank forming a key-slot in blank and shaping the punching to pass through the key slot for attaching the yoke to a coupler-shank.

7. That improvement in making railway draft-gear which consists in forming a blank of sufficient length to form the sides and back of a yoke, shaping and cutting key-slots in the end-portions of the blank for attachment to a coupler-shank, punching sections out of the blank to form draft-gear openings, bending and doubling the blank to bring the key-slots and openings into juxtaposition to form a one-piece yoke with a draft-gear pocket therein, and shaping one of the punchings to form a key adapted to connect the yoke to the shank.

8. That improvement in the manufacture of railway draft-gear yokes which consists in cutting a plurality of openings adapted to receive follower plates and draft-gear in a bar of metal, doubling and bending the bar about its medial portion to form a one-piece open-sided yoke and so that said openings will be transversely alined, cutting key-slots in the sides adjacent one end of the yoke and forming integral reinforcements at said slots.

SIGVARD SIMONSON.
